UNITED STATES PATENT OFFICE.

OTTO VON BRONK, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

ARRANGEMENT FOR GENERATING ELECTRIC OSCILLATIONS.

Application filed February 26, 1924, Serial No. 695,158, and in Germany March 10, 1923.

This invention relates to an arrangement for generating high frequency electric oscillations such as are used in radio work.

An object of the invention is to provide

5 a generator of high frequency oscillations which comprises a source of audio frequency and means for tuning and then amplifying a harmonic of the audio frequency wave, the said harmonic being the radio frequency desired.

10 This and further objects will be apparent from the following description when taken with the accompanying drawing in which the single figure illustrates a simple embodiment of the invention.

15 It is a fact that if a telephone receiver connected in circuit with a telephone transmitter in the usual manner, be placed near the transmitter in such a way that sound waves 20 sent out by the receiver diaphragm act directly on the transmitter, undamped oscillations will be produced, resulting usually in an audible howl. This fact up till now has been of no importance in the production 25 of radio frequency waves because the production of waves of more than 2000 cycles per second causes difficulties because of the mechanical inertia of the receiver and transmitter.

30 According to the present invention radio frequency oscillations can be produced by means of the microphone-buzzer in such a way that the frequency generated by the microphone-buzzer acts on an oscillatory circuit which is tuned to a harmonic of the audio frequency, which harmonic may be the radio frequency desired. This radio frequency circuit may then be coupled to the grid-filament circuit of an amplifier valve, 35 in the plate-filament circuit of which is an oscillatory circuit tuned to the frequency of that harmonic. By this means undamped oscillations of highest frequencies can be generated without regeneration or a coupling reaction of the plate-filament circuit 40 to the grid circuit being necessary as in the normal vacuum valve generator. As the frequency of the microphone-buzzer can be altered as required by adjoining acoustic resonators the frequency of the harmonics 45 can also be altered correspondingly.

50 The drawing shows schematically one example of the present invention. The alterations of current caused by microphone 1, 55 which are led thru the primary of trans-

former 2, the secondary of which is connected to buzzer 3, act on microphone 1, and the system operates according to the principle of the regenerative microphone-buzzer. In the audio frequency circuit the oscillatory 60 circuit 4 tuned to a harmonic is inserted and connected to the grid-filament circuit of the valve 7 by the radio frequency coupling 5. An adjustable auxiliary voltage may be applied to the grid 6 in order to work on a 65 suitable part of the valve characteristic curve. In the plate-filament circuit of valve 7 there is another oscillatory circuit 8, tuned to the same harmonic, which may be coupled, for example, to an aerial 9. Of course the 70 frequency can, if necessary, be further multiplied in any of the ways known.

It is essential that the coupling between circuit 4 and the grid-filament circuit of the valve be so loose that only the harmonic is 75 transferred. Choke coils or filter circuits can, if necessary, be inserted between the circuits, and in addition the grid-circuit may be tuned to the required radio frequency.

Having described one embodiment of my 80 invention I wish it understood that my invention is not limited to the embodiment disclosed but is limited only as defined by the following claims:

1. An arrangement for producing radio 85 frequency oscillations comprising a circuit in which a telephone transmitter and receiver are so connected that audio frequency oscillations are produced thru regeneration, a second oscillatory circuit tuned to a 90 harmonic of the audio frequency and connected in said first circuit, and means for leading off the said harmonic loosely coupled to said second circuit so as to pass only the harmonic. 95

2. In combination, a microphone, a magnetic receiver placed in acoustic relation therewith and electrically coupled thereto by means of an iron core transformer for the production of alternating current of 100 fundamental frequency, a resonant circuit including an air core transformer in series with one of the transformer circuits and tuned to a harmonic of the fundamental frequency, and a vacuum tube amplifier tuned 105 to the harmonic coupled to the air core transformer.

3. The combination with means to generate a fundamental frequency comprising two coupled circuits, a variable impedance 110

element and an electro-magnetic vibratory element in physically cooperative relation and electrically connected one in each of said coupled circuits, of a resonant circuit tuned to a harmonic of the fundamental frequency connected in one of said coupled circuits.

4. Means to generate a radio frequency under audible control comprising a microphone-buzzer tuned to an audio frequency, 10 and a resonant circuit tuned to a radio frequency harmonic of the audio frequency connected in the microphone-buzzer circuit.

OTTO von BRONK.
